CLAIM

The ornamental design for a sports equipment head, as shown and described.

DESCRIPTION

FIG. 1 is front top left perspective view of a sports equipment head showing my new design.

FIG. 2 is a bottom rear perspective view thereof.

FIG. 3 is a front elevation view thereof.

FIG. 4 is a rear elevation view thereof.

FIG. 5 is a right side elevation view thereof.

FIG. 6 is a left side elevation view thereof.

FIG. 7 is a top plan view thereof; and,

FIG. 8 is a bottom plan view thereof.

The broken lines showing the fragmented shaft of the sports equipment head forms no part of the claimed design.
